Filed June 1, 1971, Ser. No. 149,093

Term of patent 14 years

Int. Cl. D30—02

U.S. Cl. D30—1

FIG. 1 is a fragmentary end, top and side perspective view of an A-frame poultry house, showing my new design, a portion being broken away and omitted to show the interior, and another portion being broken away and omitted to indicate indeterminate length;

FIG. 2 is a fragmentary top plan view, a part being broken away and omitted to indicate indeterminate length;

FIG. 3 is an end elevational view; and

FIG. 4 is a cross-sectional view, partly in end elevation, taken on line 4—4 in FIGS. 1 and 2.

The interior shown in FIGS. 1 and 4 is continuous throughout the length of the house.

I claim:

The ornamental design for an A-frame poultry house, as shown and described.
